UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed March 26, 1924. Serial No. 701,982.

To all whom it may concern:

Be it known that I, NORMAN B. HURD, a citizen of the United States of America, residing at New Britain, Connecticut, have invented a new and useful Lock, of which the following is a specification.

My invention relates to a lock.

It is at the present time common practice to provide a lock with a stop action for locking one of the thumb pieces or other latch actuators so that the latch can be operated from only one side, that is to say, the stop action is so arranged that when in one position the outside thumb piece or other actuator will be dogged, so that the latch cannot be operated from the outside but can be retracted from the inside of the door.

When such a lock is to be put on the opposite door, what was formerly the inside of the lock would then become the outside, and some rearrangement is necessary to enable the then outside thumb piece to be dogged, to prevent operating the latch from the then outside.

It is the general object of my invention to provide a lock which may be used on either a right or a left hand door, and the latch dogged from the outside in either case.

It is another object to provide a lock having simplified dogging means for dogging the latch from either side of the lock.

It is a more specific object to provide a locking dog which, by a simple reversal, may be caused to dog a latch from either side of the lock.

Briefly stated, the invention in its preferred form includes a lock which may be of a conventional type and including a latch to be operated by means on both the inside and the outside of a door. A locking dog is placed in the path of one of the latch retracting means, and may be locked in that position by means of a stop action, so as to prevent actuation of the latch from the outside of the door. The locking dog is of such form that upon a mere reversal of that part it will come in the path of the other latch actuator and may be locked in that position, so as to prevent actuation of the latch by the last actuator.

In the drawings, which show, for illustrative purposes only, a preferred form of the invention—

Fig. 1 is a fragmentary view of the outside of a left-hand door with a lock applied

thereto, parts being broken away to illustrate features of the invention;

Fig. 2 is a fragmentary view of the features shown in Fig. 1, looking upwardly;

Fig. 3 is a sectional view of parts shown in Fig. 1 as viewed from the left in Fig. 1;

Fig. 4 is a detail view of parts shown in Fig. 1 but differently arranged;

Fig. 5 is a perspective view of an improved locking dog.

The lock 1 is applied to a door, and in the form shown the lock is reversible, so that the same may be applied to either a right or a left hand door. The lock is provided with the usual locking bolt and mechanism (not shown) for actuating the same by means of a key. 2 indicates a conventional type of latch urged to the outward position by means of a spring 3, interposed between the latch case and a head 4 on the latch bolt. A latch lever 5 in the preferred form is pivoted on a pin 6 in the casing, and the end 7 engages the latch bolt so as to retract the latch. When the lock is arranged for actuation by thumb pieces, the latter are usually arranged at a point beneath the lock. In the form shown the conventional thumb pieces 8-9 are pivoted, respectively, at 10-11, and the inner ends 12-13, respectively, which may be termed thumb levers, extend to points beneath the lower end of the latch lever 5. It will now be clear from Figs. 1 and 3 that, upon depressing either of the thumb pieces 8 or 9, one of the thumb levers 12 or 13, depending upon which thumb piece is depressed, will rock the latch lever 5 about its pivot pin 6, and the extreme end 7 will retract the latch 2.

As has been stated above, it is desirable to dog the outside thumb piece or thumb lever so that it will be impossible to open the door by depressing the outside thumb piece. In the form shown I provide what may be termed a locking dog 15, which if desired may be pivoted on the pin 6. The locking dog has two projecting portions 16-17 at opposite sides thereof, and these projections are offset relatively to each other. While these projections may truly be termed projections it would be equally as well to define same by stating that the locking dog is provided with cutaway portions, 18, 19 which are offset relatively to each other.

When the locking dog is arranged in the position shown in Fig. 1, the projection 17

extends down to the plane of the lower end of the latch lever 5, while the cut-away portion 18 is raised considerably above the lower end of the lever 5. It will thus be clear that if the latch dog 15 is locked in the position shown in Fig. 1, the thumb lever 13 extending beneath both the latch lever 5 and the locking dog 15 cannot be raised to actuate the latch. With the locking dog in the position shown in Fig. 1, it will be equally clear that the same will have no effect upon the thumb lever 12 on the inside of the door which will be free to actuate the latch 2. Means must therefore be provided for dogging or holding the locking dog 15 in the position shown in Fig. 1. The means which I employ may be a stop action, including the usual push buttons 20-21, carrying the inner extensions, which are caused to move in predetermined fashion by the link or connecting lever 22 on the interior of the lock case. A suitable snap action means, such as the spring 23, serves to hold either of the push buttons in depressed position. The extreme end of one of the extensions, in the present case the extension 24 on the push button 21, extends, when the push button 21 is depressed, into the path of the end 25 of the locking dog 15. When the push button 21 is depressed, the end 24 will serve to effectively lock the locking dog in the position shown in Fig. 1. When the push button 20 is depressed, the end 24 will be withdrawn from the path of movement of the end 25 of the locking dog, and the same will then, of course, be free to move. With the parts arranged as shown in Fig. 1, therefore, the outside thumb piece 9 and its corresponding thumb lever 13 would be effectively dogged, so that it would be impossible to depress the thumb piece 9 so as to cause the lever 13 to retract the latch 2. The inner thumb piece 8 and its corresponding lever 12, due to the cutaway portion 18, will be free to act upon the lower end of the latch lever 5, so as to retract the latch 2.

Now, when it is desired to use the lock on a right hand door, it is necessary to reverse the latch 2, as in all locks of this character, and it is also necessary to reverse the cylinder portion of the lock. Now, in order to permit the thumb piece 8, which would then be the outside thumb piece, to be dogged so as to prevent actuation of the latch 2 from the outside, it is only necessary to lift the locking dog 15 off of the pin 6 and reverse the same and replace it upon the pin. This reversed position is shown in Fig. 4. Now, since the projection 16 extends down adjacent the lower end of the latch lever 5 and directly in the path of the thumb lever 12 carried by the thumb piece 8, when the push button 21 is de-

pressed, so as to be in the position shown in Fig. 1, it will be clear that the thumb piece 8, which is now on the outside, will be effectively dogged, so as to prevent retraction of the latch 2 from the outside 70 of the door. When the button 20 is depressed, the end extension 24 is withdrawn and, of course, the latch may then be retracted by depressing either thumb piece.

The locking dog which, by a simple reversal, may serve to lock either latch actuator so that the lock may be used on either a right-hand or a left-hand door, constitutes the principal feature of my invention. Other devices are now known for rearranging locks so that the same may be used on either right or left hand doors, but with all of the arrangements with which I am familiar there are several parts which must be adjusted and rearranged, and all lack the simplicity so characteristic of my present invention.

While I have disclosed a preferred form of the invention, I do not wish to be limited to the form shown since changes may be made within the scope of my invention as defined in the appended claims.

I claim:

1. In a lock, a latch, separate means at opposite sides of said lock for retracting said latch, a single reversible locking dog having blocking means to be positioned in the path of one or the other of said retracting means depending upon the mounted position of said dog, and means for locking said locking dog whereby said latch will be locked against retraction by one of said means.

2. In a lock having a latch and a latch lever for actuating the same, said latch lever being pivoted in the lock case, a pair of thumb levers for retracting said latch, a single reversible locking dog adjacent said latch lever, said locking dog having a part to be engaged by one of said thumb levers when mounted in one position, and another part to be engaged by the other of said thumb levers when mounted in another position, and a stop action for locking said locking dog.

3. In a lock including a latch, a pivoted latch lever for actuating the same, a single reversible locking dog pivoted with said latch lever, a pair of thumb levers for actuating said latch lever, said locking dog having a part extending into the path of one of said thumb levers when mounted in one position, and when reversed having a part extending into the path of the other thumb lever, and means for locking said locking dog.

4. In a lock including a latch, a latch lever for actuating the same, a locking dog having two projecting lugs, one at each side thereof, a pair of thumb levers for actuati-

ing said latch lever, one of the projections on said locking dog lying in the path of movement of one of said thumb levers when the locking dog is in one position, and the 5 other projection lying in the path of the other thumb lever when the locking dog is in reversed position, and a stop action for locking said locking dog whereby either of said thumb levers may be prevented from 10 actuating said latch lever.

5. In a lock, a latch, a latch lever for actuating the same, a pivot pin for pivoting the latch lever in the lock case, a locking dog pivoted on said pin with said latch lever, 15 a pair of thumb levers for actuating said latch lever, said locking dog having a part extending into the path of each of said

thumb levers, depending upon the position of said locking dog, and stop action means for locking said locking dog whereby either 20 of said thumb levers may be prevented from actuating said latch lever.

6. As an article of manufacture, a locking dog for the purpose herein described, comprising a plate having a projection at each 25 side thereof, said projections being offset relatively to each other.

7. As an article of manufacture, a locking dog for the purpose herein described, comprising a plate having a cutaway portion at 30 each side, said cutaway portions being offset relatively to each other.

NORMAN B. HURD.
